FINISHING MACHINE

Rocco Monforte, Saylesville, R. I.

Application June 12, 1935, Serial No. 26,123

7 Claims. (Cl. 12—77)

My invention relates to finishing machines for the soles and heels of shoes, and more particularly to the tools for heating or burnishing the same.

5 In this type of machine various tools, usually mounted upon a single shaft, are intermittently employed for performing various finishing operations upon a shoe. This occasional use of the burnishing tool makes it necessary to reheat the latter on each occasion, and to accomplish the heating step with speed. The heat is commonly generated by means of a lever impelled friction element manually moved into contact with the burnishing tool for the necessary period to 10 accomplish this purpose, and thereafter withdrawn by a reversal of the lever.

20 Heretofore the means for effecting this end has involved the employment of an unnecessarily large number of parts with resultant effort, delay and uncertainty of operation, as well as great initial cost, and expense of upkeep; and such parts have exposed the hand of the operator to injury.

25 The essential objects of my invention are to overcome the defined disadvantages, and insure speed and certainty of action, facility of operation, safety to the operator, distributing the wear and compensating for the wear upon the frictional element, economy, and simplicity.

30 Other and ancillary objects of my invention will hereinafter appear.

To the above recited and indicated ends essentially my invention consists in such parts and in such combinations of parts as fall within the scope of the appended claims.

35 In the accompanying drawing which forms a part of this specification,

Figure 1 is a perspective view of my invention embodied in a finishing machine with the operating parts shown in unlocked or running position in full lines, and in locked position in broken lines,

40 Figure 2, a longitudinal section partially in plan elevation taken on line 2—2 of Figure 1, with the parts in locked position,

45 Figure 3, a detailed perspective view of my device in running position looking in a direction opposite to that from which the view in Figure 1 was taken,

50 Figure 4, an enlarged fragmentary top plan view of the lower or forward end of the housing with the parts in substantially the position shown in Figure 1, and

55 Figure 5, a fragmentary view of the same showing the cooperating opposite slot.

Similar letters of reference indicate similar parts throughout the views.

My device is shown in Figure 1 as carried by the projecting end of the frame tie rod 9 supported in the standards 10, only one being shown, which standards also rotatably support the usual sectional arbor or driving shaft 11 of a finishing machine. The metal burnishing tool 13, rigid upon the arbor, includes a burnishing portion 14, and an adjacent annular shoulder portion 15. 10

A tubular casing or housing 17 includes, a closed rear end 19, and an open forward end 20. A lateral tubular extension or socket 21 integral with an intermediate portion of the housing is attached to the rod 9 by a threaded connection 15 as at 22. The casing is herein illustrated disposed at right angles to the burnishing tool, but downwardly inclined with relation thereto in a vertical plane, with its depressed forward end spaced from the tool. 20

Slidable in the housing is a friction element 24, composed of a fiber, rubber, or other material suitable for generating heat when in operating contact with a rotary burnishing tool, and provided with a plurality of holes 25 arranged in a longitudinal series, in this instance three in number. 25

A helical spring 27 in the casing 17 has its opposite ends abutting against the portion 19 of the latter and the friction element 24 respectively, and acts as an expansion spring to urge said element towards the tool 13. 30

An arcuate guide slot 29 in the forward portion of the casing side or wall 18 extends gradually rearwardly and outwardly or laterally thereof, the lateral curvature being in a direction away from the socket 21, and terminates at its outer end with a forwardly directed locking notch or recess 30. In the present instance the slot bounds approximately a quadrant. 35

In a diametrically opposite portion of the casing wall is formed a guide slot 33 cooperating with the slot 29 and of the same length and contour as the latter, but with its lateral curvature directed oppositely to that of the first slot. The second slot terminates in a forwardly directed locking notch or recess 34 diametrically opposite the notch 30. 40

A guide member 36 comprises a locking pin 37 and a handle 38. The pin is frictionally but removably engaged with the element 24 in the lowermost of the holes 25, and loosely traverses both the slots and/or notches, while the handle is integral with or fixed to the pin. 50

The lowermost of the holes 25 is so located 55

Figure 5, a fragmentary view of the same showing the cooperating opposite slot.

5 relatively to the front end of the friction element 24 that when the pin 37 rests in the locking notches 30 and 34 the end of said element is spaced from the tool 13, as shown in full lines in Figure 2, and this is the locked or inactive position of my device.

When it is desired to advance the element 24 into contact with the rotating burnishing tool 13 to heat the latter, the operator, standing in 10 front of said tool, manually lifts or pushes the handle 38 out of the notches 30 and 34 and instantly the spring 27 impels the forward end face of the member 24 into contact with the flat periphery of the shoulder 15 of the tool 13, 15 as shown in broken lines in Figure 2, simultaneously moving the pin 37 forwardly in the arcuate slots 29 and 33 and thereby imparting a twist, spiral, or transversely arcuate motion to the advancing pin. In full lines in Figures 1, 3, 4 and 20 5, the running position of the pin 37 is shown intermediate the ends of the guide slots under continuous pressure of the spring.

When the burnishing operation is completed 25 the operator, by a single diagonal thrust of the palm of his hand against the handle 38 towards the rear of the casing and laterally away from the socket 21, returns the pin to its locked position against the pressure of the spring 27. The direction and character of this thrusting movement prevents accidental contact of the hand 30 with the machine frame.

One result of the rotary or circular character 35 of the advance of the frictional element 24 is that as the pin 37 gradually approaches the forward ends of the guide slots the end face of the element 24 turns to present a comparatively new point of contact with the surface of the tool, thus distributing the wearing area of the former within the limits permitted by the arcuate slots 29 and 33, and consequently the degree 40 of wear upon the end face of the element 24.

When, however, the ultimate wear upon the 45 end of the element 24 is such that the pin 37 reaches the forward limits of the guide slots, the rod may be withdrawn from the lowermost of the holes 25 and be snugly inserted in the next higher hole.

The described heating apparatus is simple in 50 construction, easily assembled, and certain and speedy in action. No support auxiliary to the usual tie rod of the machine is required to carry the casing 17. The danger and expense incident to exposed and complicated mechanical parts prevalent in earlier structures are absent.

55 While I have described a specific constructional embodiment of my invention, it is obvious that desired changes in the arrangement and the size of the parts and in their function and operation, may be made without departing from the spirit and the scope of the invention as defined in the appended claims.

I claim:

60 1. A heater comprising a friction element adapted for engagement with a moving tool, a casing for said element provided with a transversely curved slot, said element being arranged

5 to spirally slide in the casing, yielding means tending to cause said element to advance into contact with the tool, and means controlled by said slot for imparting a spiral movement to said element during its advance.

2. A heater comprising a casing provided with a longitudinally and transversely curved guide slot, a friction element adapted for engagement with a moving tool and slidably mounted in the casing, yielding means adapted to impel said element towards the tool, and a guide member comprising a pin engaging said frictional element and slidable in the slot, and a handle upon the end of the pin.

3. A heater comprising a casing provided with a spiral guide slot terminating at one end in a notch, a friction element adapted for engagement with a movable tool, said element being adapted to slide in the casing, resilient means adapted to impel the element against the tool, 20 a locking pin engaging said element slidable in the slot and registerable in the notch, and a handle upon the pin.

4. A heater comprising a casing provided at 25 one end with a curved guide slot one end of said slot terminating in a notch, a friction element adapted for engagement with a movable tool, said element being longitudinally slidable in the casing and provided with a plurality of 30 holes disposed in longitudinal series, resilient means in the casing for actuating the friction element, a locking pin in one of the holes slidable in the slot and registerable in the notch, and a handle upon the pin.

5. A heater comprising a casing provided at 35 one end with a spiral guide slot, said slot terminating in a locking notch, a second slot and locking notch diametrically opposite to the above mentioned slot and notch, a friction element 40 adapted for engagement with a moving tool and slidably mounted in the casing, a spring in the casing for advancing the element to the tool, a locking pin in said element slidable in the slots and registerable in the notches, and a handle 45 upon the pin.

6. A heater comprising a casing provided with a guide slot terminating at one end in a locking notch, a friction element adapted to engagement 50 with a movable tool, said element being adapted to longitudinally slide in the casing, resilient means in the casing for impelling the element against the tool, a locking pin in said element slidable in the slot and registerable in the notch, and a handle on the pin.

7. In a finishing machine, a tie rod, an elongated casing, a socket upon the side of the casing having a threaded engagement with the tie rod, said casing being provided upon opposite sides with curved slots terminating in locking 60 notches, a friction element slidably mounted in the casing, an expansible spring in the casing engaging the rear end of said element, a locking pin carried by the tool slidable in the slots and registerable in the notches, and a handle 65 upon the pin.

ROCCO MONFORTE.
